UNITED STATES PATENT OFFICE.

JOSEPH OPPERUD, OF MADISON, SOUTH DAKOTA.

RUBBER HEEL.

1,189,472.

Specification of Letters Patent.

Patented July 4, 1916.

Application filed January 5, 1916. Serial No. 70,456.

To all whom it may concern:

Be it known that I, JOSEPH OPPERUD, a citizen of the United States, residing at Madison, in the county of Lake and State 5 of South Dakota, have invented certain new and useful Improvements in Rubber Heels, of which the following is a specification.

This invention relates to rubber heels and more particularly to that class of heels having means for prolonging their life.

The principal object is to provide a heel of the class described that will have a metal wear plate embedded therein in such a manner as not to impair the elasticity of the 15 heel.

A further object is to provide a wear plate that will be so constructed that it will hold itself in position without the use of tacks, nails, etc.

20 Other objects and advantages such as simplicity, durability, cheapness in manufacture and the general improvement of the art will be more fully brought out in the following specification and illustrated in the 25 accompanying drawings, in which:

Figure 1 is a side view of a shoe with my improved heel attached; the heel being broken away on the line 1—1 of Fig. 2, Fig. 2 is a plan view of the bottom of the heel, 30 Fig. 3 is a sectional view of my improved heel on the line 3—3 of Fig. 2, Fig. 4 is a side elevation of the wear plate of my improved heel, Fig. 5 is a plan view of a modification of my wear plate, and Fig. 6 is a 35 side elevation of the modification shown in Fig. 5.

Referring more particularly to the drawings, A designates a shoe having a rubber heel 1 with my improved plate 2 embedded 40 therein. The plate 2 consists of a wear portion 3 and retaining prongs 4 and 5 and retaining prongs 6 and 7. The retaining prongs 4 and 5 extend inwardly and are integral with the portion 3 and bent upwardly 45 so that their lower faces are substantially in alinement with the upper face of the portion 3. The prongs 6 and 7 are bent upwardly and then back over the wear por-

tion 3. The portion of the prongs extending over the portion 3 being on a line parallel therewith.

The plate described above is adapted to be embedded in a rubber heel during its construction and the prongs 4 and 5 serve to retain and also distribute the strain of the 55 metal within the rubber. The prongs 6 and 7 are the main retaining prongs. The peculiar shape of these prongs prevents the plate from slipping backward or downward.

It is obvious that from the construction of 60 the plate as described and shown it needs no securing means other than the prongs and that any impairment of the elasticity of the heel is thus avoided. The cheapness of 65 manufacture of the plate will also be obvious since it may be stamped out in one operation and pressed into shape in a second operation.

In Fig. 5 I show a modification of my device which consists of the usual wear portion 70 3, but has a retaining plate portion 8 instead of the prongs 4 and 5. A portion of the retaining plate 8 is pressed out and bent upwardly and over the wear portion 3 forming a single retaining prong 9. 75

It will be understood that I may change the details of construction and shape of my improved plate within the scope of the appended claims without departing from the spirit of my invention.

Having thus described my invention what I claim is:

1. In a heel having a rubber body portion, a metal wear plate embedded in said body portion, said plate comprising a wear portion, a portion extending laterally from the inner edge of said wear portion into said heel, and another portion bent upwardly from the inner edge of said wear portion and laterally so that it is spaced from and 85 parallel with said wear portion.

2. A wear plate for heels comprising a wear portion and retaining portions, said retaining portions comprising a plurality of retaining prongs extending laterally in one 90 direction from one of the edges of said wear 95

portion, and a second plurality of retaining prongs extending laterally from the same edge in the opposite direction.

3. A wear plate for heels comprising a wear portion and retaining portions, said retaining portions comprising a plurality of retaining prongs extending upwardly and laterally in one direction from one of the

edges of said wear portion, and a second plurality of retaining prongs extending upwardly and laterally from the same edge in the opposite direction.

In testimony whereof I hereto affix my signature.

JOSEPH OPPERUD.
